UNITED STATES PATENT OFFICE.

JOHN W. STREET, OF SALEM, OHIO.

IMPROVEMENT IN HARVESTERS.

Specification forming part of Letters Patent No. 35,901, dated July 15, 1862.

To all whom it may concern:

Be it known that I, JOHN W. STREET, of Salem, in the county of Columbiana and State of Ohio, have invented certain new and useful Improvements in Machines for Harvesting Grain and Grass; and I do hereby declare the following to be a full and exact description of the same, reference being had to the accompanying drawings, making part of this specification, in which—

Figure 1 is a plan of my improved machine, partly in section. Fig. 2 is a side elevation of the same. Fig. 3 is an inside view of the ratchet-box, hereinafter described. Fig. 4 is a fragmentary perspective view of the connection between the pitman and cutter-bar.

Similar letters of reference indicate corresponding parts in the several figures.

The nature of the invention consists, first, in an improved construction of ratchet for connecting or disconnecting the wheels with the driving-shaft; second, in an improved manner of constructing and mounting the intermediate gear-wheels by which motion is communicated from the driving-shaft to the cutting apparatus; third, in an improved construction of drag-frame; fourth, in an improved manner of hinging the finger-bar to the drag-frame.

To enable others skilled in the art to make and use my invention, I will proceed to describe its construction and operation.

A is the main frame, formed with hounds *a* for the attachment of the tongue, and with rigid hollow stud-shafts *a a*, upon which the carrying and driving wheels *B B'* turn.

C is a shaft extending from side to side of the frame A, completely through the stud-shafts *a a*, and provided at each end with a box, D D', which may be of equal diameter with the hubs of the wheels *B B'* and serve to retain them on their journals. One or both of the boxes D D' may be provided with pivoted pawls *d d*, which, when motion is to be communicated to the cutting apparatus, are held in or out of gear with ratchet-teeth *b* on the face of the wheel-hub by means of an elastic lever, E, fulcrumed upon the shaft C and projecting on each side of the box D through slots therein of sufficient length to admit of turning the said lever, so that it shall bear against either end desired of the pawls. By setting the lever so as to bear against the hooked or

toothed ends of the pawls the latter will take firmly into the teeth on the wheel-hub, and thereby the motion of the wheel will be communicated through the pawls *d* and box D to the shaft C. By turning the lever E so as to bear against the rear ends of the pawls *d* the latter will be held out of contact with the teeth upon the wheel B, and the latter will then be free to turn without operating the cutting apparatus. When the motion of the wheel is reversed, the elasticity of the lever E permits the pawls to slip over the teeth *b*, so that no motion is imparted to the cutter.

F is a gear-wheel keyed upon the shaft C and meshing with a pinion, G, which is secured upon a sleeve, *g*.

G' is a bevel-gear, which is also secured upon the sleeve *g*. The said sleeve turns freely upon a secondary shaft, H, journaled transversely in the forward part of the main frame.

I I' I² J J' represent a drag-frame attached in front to the shaft H. The said drag-frame is constructed as follows: I I² represent a casting of L form, having an eye in front for attachment to the shaft H. I' is a second cast eye, also intended for attachment to the shaft A. J J' are two wrought or malleable rods, which are laid in the molds before the casting is made, in such positions that their forward ends will be embedded in the eye I', the rear end of the rod J in the angle of the L, and that of the rod J' at the outer end of the transverse arm, so that the rod J' shall constitute one of two parallel sides of the frame, and the rod J a diagonal brace. The flange I², projecting downward from the outer rear corner of the drag-frame, may either rest directly upon the ground, or may be supported upon a shoe of any suitable construction.

K is the finger-bar, secured by a horizontal hinge, l, to a plate, L, which plate is attached by a diagonal hinge, l', to the outer face of the flange I².

N is the reciprocating cutter.

O is a shaft running in bearings o o on the drag-frame, and having secured to its upper end a bevel-pinion, P, which meshes with the bevel-gear wheel G'. The lower end of the shaft O carries a crank-wheel, Q, which imparts a reciprocating motion to the pitman or connecting-rod R, and thus to the cutter-bar. The connecting-rod is attached to the cutter

by a universal joint constructed as follows: n is a socket hinged at n' to the end of the cutter-bar. The said socket is secured upon the end of the pitman by means of a pin, r , passing through the pitman and through slots n'' in the opposite sides of the socket n , as clearly shown in Fig. 4. By these means the cutter is made free to turn upon the pitman as the bar rises and falls, and especially when it is folded up for transportation. The latter position of the bar is shown in red in Fig. 2.

S is the driver's seat.

T is a lever fulcrumed upon the main frame and connected by a chain to the drag-frame for the purpose of raising the latter.

Other portions of the machine may be constructed in any suitable manner, and require no specific description.

The manner described of journaling the driving wheel or wheels upon hollow shafts projecting from the sides of the machine and through which the main gear-shaft passes, relieves the gear-shaft of much friction and wear and causes the gearings to work more smoothly and with less clatter.

The crank-wheel Q is perforated for the attachment of an extension-shaft, which may be bolted thereto, as shown in red at U in Fig. 1. The object of this is to adapt the machine to

be used for the purpose of a horse-power when secured in an upright position by means of a frame of suitable construction.

Having thus described my invention, what I claim therein as new, and desire to secure by Letters Patent, is—

1. The lever E , (elastic or otherwise,) fulcrumed upon the shaft C and projecting on each side of the box D , for the purpose of throwing the pawls $d d$ in and out of gear, substantially as explained.

2. Mounting the two independently and separately cast intermediate gear-wheels, G and G' , upon a common sleeve, g , which sleeve is journaled upon the shaft H , which hinges the drag-frame to the main frame A .

3. The drag-frame I I' I'' J J' , constructed and employed in the manner and for the purposes described.

4. Attaching the finger-bar by a diagonal hinge, l , on either a perpendicular or horizontal side of the drag-frame, shoe, or finger-bar, (with or without the horizontal hinge l ,) to admit of folding the bar for transportation, substantially as described.

JOHN W. STREET.
